UNITED STATES PATENT OFFICE.

FRANCIS HODGKINSON, OF EDGEWOOD PARK, PENNSYLVANIA, ASSIGNOR, BY MESNE ASSIGNMENTS, TO THE COLONIAL TRUST COMPANY, TRUSTEE, OF PITTSBURGH, PENNSYLVANIA, A CORPORATION OF PENNSYLVANIA.

MEANS FOR BLEEDING TURBINES FOR INDUSTRIAL PURPOSES.

1,071,420.

Specification of Letters Patent. Patented Aug. 26, 1913.

Application filed October 8, 1909, Serial No. 521,745. Renewed June 8, 1912. Serial No. 702,634.

To all whom it may concern:

Be it known that I, FRANCIS HODGKINSON, a subject of the King of Great Britain and Ireland, and a resident of Edgewood Park, in the county of Allegheny and State of Pennsylvania, have made a new and useful Invention in Means for Bleeding High-Pressure Steam from Turbines for Industrial Purposes, of which the following is a specification.

This invention relates to turbines and particularly to means for bleeding motive fluid from the turbine and for utilizing it for heating or for industrial purposes.

An object of this invention is to produce means for delivering motive fluid from a turbine and for maintaining the fluid pressure approximately constant in the turbine at the point of delivery.

It is frequently desirable to employ steam, at a pressure lower than the available pressure, in heating systems or for use in cooking or other industrial purposes and it is of course desirable to conserve the energy of the steam and to employ the expansive force in performing useful work. With my invention I am able to deliver steam of any pressure ranging from boiler pressure to condenser pressure and to utilize the steam most efficiently.

In the drawings accompanying this application and forming a part thereof;

Figure 1 is a longitudinal section on the line 1—1 of Fig. 2 and illustrates a turbine of the Parsons' type equipped with my invention; and Fig. 2 is a transverse section along the line 2—2 of Fig. 1.

Referring to the drawings, the turbine shown is divided into three stages, an initial or high pressure stage 3, an intermediate stage 4 and a low pressure stage 5. Motive fluid is delivered to the turbine through an inlet port formed in the turbine casing 6 and communicating with an annular passage 7 which is located within the casing and surrounds the rotor element of the turbine. The chamber 7 communicates directly with the admission end of the high pressure stage 3 and the motive fluid, in traversing the turbine, passes successively through the high, intermediate and low pressure stages and is discharged from the turbine through an ex-

haust port 8 provided in the turbine casing. The fluid in traversing the working stages of the turbine is expanded and the pressure varies throughout the length of the turbine from initial or inlet pressure to exhaust pressure.

In the drawings, I have illustrated means for delivering the fluid discharged from the intermediate stage of the turbine to a coil 9 which may be employed for heating or for any other industrial purpose. I have also shown means for maintaining the fluid pressure at the exhaust end of the intermediate stage 4 approximately constant or constant within close limits. I provide a partition 11 on the casing 6 of the turbine which projects into close proximity with the turbine rotor and is provided with a fluid seal of ordinary construction which is located between it and the rotor. This partition 11 divides the turbine into two parts so that the fluid discharged from the intermediate stage 4 cannot enter the final stage except by traversing a port 13 formed in the casing, a passage provided within a valve casing 14 and a port 15 provided in the turbine casing. The casing 14 is provided with ports 16 which are controlled by a valve 17 and through which the fluid must pass in its passage from the port 13 to the port 15. A port 18 is provided in the turbine casing 6 and is located between the exhaust end of the stage 4 and the valve 17. Piping 20 communicates with the port 18 and may deliver fluid to the heating coil 9 or to any other apparatus utilizing low pressure steam.

The valve 17 is provided with an adjustable weight 19 and maintains a predetermined pressure within the turbine casing at the exhaust end of the stage 4. When sufficient steam is delivered to the turbine to cause the pressure at that point to build up above the determined pressure the valve 17 is lifted and is caused to open the ports 16 and deliver a portion of the motive fluid discharged from the stage 4 to the low pressure stage 5 of the turbine. The valve 17 will open varying amounts, dependent upon the amount of steam exhausted from the stage 4, and will maintain the pressure at the inlet to the port 13 approximately con-

stant or constant within close limits. It will be apparent that the valve 17 may be spring controlled or may be replaced by any suitable apparatus for maintaining a constant fluid pressure.

In order that the longitudinal thrusts on the turbine rotor may be counterbalanced I provide balancing drums 21, 22 and 23 of ordinary construction for the high, intermediate and low pressure stages respectively. The drum 21 is exposed on one side to the inlet pressure of the stage 3. The drum 22 is exposed on one side to the inlet pressure of the stage 4 through a passage 15 24 and the drum 23 is exposed to the inlet pressure of the stage 5 through a pipe 25. The thrust occasioned by the fluid seal 12 between the partition 11 and the rotor may be balanced by making it of equal 20 diameter with the drum 22 or by making it of equal diameter with the exhaust end of the stage 4 as shown in the drawings.

Having now described my invention, what I claim is:—

1. In a multi-stage turbine, a dividing partition between two adjacent stages, a port located on the admission side of said partition for delivering fluid from said turbine, a passage around said partition, and a valve in said passage the operation of which is dependent upon the pressure on the admission side of said partition for controlling the delivery of fluid around said partition.

2. In a two-bearing multi-stage steam turbine, a dividing partition between two adjacent stages, a port located on the admission side of said partition for delivering fluid from said turbine, a steam passage around said partition, and a valve the operation of which is dependent upon the pressure on the admission side of said partition for controlling the delivery of fluid around said partition.

3. In a multi-stage two-bearing steam turbine, a partition between two adjacent stages for preventing steam flow between said stages, and a valved steam passage around said partition connecting said stages, in combination with means outside of the turbine and adapted to utilize a portion of the steam exhausted from the first of said two stages.

4. In a multi-stage two-bearing steam turbine, a partition dividing the interior of said turbine into two parts and adapted to prevent steam flow between said parts, a bleeder port located on the high pressure side of said partition, a steam passage around said partition connecting said parts, a controllable valve in said passage, and means the operation of which is dependent upon the pressure of the steam on the high

pressure side of said partition for controlling said valve.

5. In a multi-stage steam turbine, a partition dividing the interior of said turbine into two parts, a steam passage around said partition for placing said parts in communication, a valve in said passage, and means the operation of which is dependent upon the pressure of the steam on the inlet side of said valve for controlling said valve, in combination with means outside of the turbine and in steam connection with the inlet side of said valve for utilizing steam from said turbine.

6. In a turbine, means for dividing the interior passages of the turbine into two parts, a port located in the turbine casing on the admission side of said means for delivering fluid from said turbine to a source of consumption outside the turbine, a port in the dividing means whereby steam may pass from one part of the turbine into the other, and a valve for maintaining a constant pressure in that part of the turbine from which the first named port leads, said valve being controlled by pressure to determine the effective port area of the second mentioned port.

7. In a turbine, a partition dividing the interior passages of the turbine into two parts, a port located on the admission side of said partition for delivering fluid from said turbine, and a valve the operation of which is dependent upon the pressure on the admission side of said partition controlling the delivery of fluid around said partition from one part of the turbine to another.

8. In a turbine, means for dividing the interior passages of the turbine into two parts, a port located in the turbine casing on the admission side of said means for delivering fluid from said turbine, and a valve for maintaining a constant pressure in one of the parts of said turbine and for controlling the delivery of fluid from one part to the other.

9. In a turbine, a partition dividing the interior passages of the turbine into two parts, a valve, the operation of which is dependent upon the pressure on the admission side of said partition, controlling the delivery of fluid around said partition and from one part of the turbine to another, and an open service port between two adjacent stages.

In testimony whereof, I have hereunto subscribed my name this 5th day of October 1909.

FRANCIS HODGKINSON.
